James Stager,
Design for the plates of the "Cottage Parlour" stove,
No 176
Patented 11 April 1848.

Des. 176

James Wager, Troy, N. Y.
Letters Patent No 176, dated 11th April 1848

The Schedule referred to in these letters Patent and
making part of the same.

To all to whom these presents shall come: Be it known
that I, James Wager, of Troy, in the County of Rensselaer,
and State of New York, have invented or produced a new
Design for the plates of the "Cottage Parlour Stove," which design is
applicable to the plates of other stoves, and that the following
is a full, clear and exact description of the same, reference being
had to the accompanying drawing making part of this Specification,
which represents the stove in perspective.

The ornamental plates are eight in number. The
body of the stove containing the fire chamber rests on a plate (a)
which is ornamented with a border of leaves; at each of the
four corners of this plate a large leaf is inserted in the border. The
register for regulating the draught is situated in the front part of
this plate, and it is ornamented with a vine which is blended with
the border of the plate (a) in front.

The body of the stove containing the fire chamber
is enclosed between four ornamented plates; the front plate (b),
which is similar to the back one, is ornamented with gothic
pannelings consisting of four or more arches and pillars, and the
upper and lower edges are bordered with Grecian ornaments;
the pannelings are filled in with arabesque work, and at each

Des. 176

end of the plate is an ornamented hollow pillar (c)

The two end plates (c), enclosing the body of the stove are alike, and consist each of a square bordered panel, filled in with arabesque work. The four plates are held together by an ornamented ring having short arms immediately over the pillars said ring, and arms being decorated on the outer periphery with a Grecian ornament and on the inner with a Roman ornament. Immediately above this ring is a plain drum which is surrounded by another ring having a Grecian border. The top plate (d) is ornamented with a double border of the Composite style, and is filled in with arabesque work, and the whole surmounted by a vase.

What I claim as my invention and desire to secure by Letters Patent is the above described and illustrated design patterns for ornamenting Stove plates.
